UNITED STATES PATENT OFFICE

LEWIS C. BUMP, OF BRANDON, VERMONT

GAME

Application filed December 27, 1928. Serial No. 328,742.

My invention relates to improvements in games; and particularly to the necessary apparatus for playing the game of croquet.

An object of the invention is to provide the devices for a croquet game adapted to be played both indoors and outdoors; and capable of being readily set up and taken down in either location.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiments of my invention, and in which:

Fig. 1 shows in perspective a stake and wicket with holders therefor according to my invention;

Fig. 2 is a section taken through the lower part of the stake on the line 2—2 of Fig. 1;

Fig. 3 is a side elevation of the stake used in the practice of my invention supported by thrusting it into the ground; and

Fig. 4 is a top plan of the wicket and holders therefor shown in Fig. 1.

On the drawings the same numerals identify the same parts throughout.

In the detailed description of the invention as presented in the drawings, I use the numeral 1 to indicate my improved form of wicket and 2 the stake, one of which is placed at both ends of the course in the usual positions. It will be understood that the customary number of wickets 1 will be employed. Each wicket comprises a frame in the form of an inverted yoke 3; and both the wickets and the stakes will have suitable means for holding them upright when they are set up for playing the game indoors. These holders are simple and easy to attach; and they serve to keep the stakes and wickets upright when utilized. For playing the game outdoors, the holders can be either employed or removed and discarded for the time being so that the stakes and the wickets can be stood up by pushing their ends into the earth.

The holders for the wickets are indicated

at 4 and have the form of bases or feet, with central protuberances 5 on top. These projections 5 will be provided with vertical bores 6 which open through the upper ends of the projections, so as to receive the lower ends of the two arms of the wicket 1. I prefer to make these supports 5 semi-circular, each being the counterpart of another, so that they can be interchangeably used. On one side they are straight and flat as indicated at 7, and when any one of the wickets is set up, with the lower ends in the holders so as to be maintained in vertical position, the straight sides or faces of the holders of the wicket should be presented towards each other. The bores 6 are worked in the projections 5 as close as possible to these faces 7; and when the wicket is used the space or passage therethrough between the lower ends thereof is free and unobstructed and of practically the same width as the distance between the lower ends of the two arms thereof.

Hence when this type of wicket is used for indoor use, with the holders 4 to support it, the croquet balls can travel through the wicket with as much freedom and no greater risk of being obstructed and deflected than exists when the wickets are set up in the usual manner outdoors by forcing the lower ends into the soil.

Each of the stakes 2 included in the set for one game will likewise be provided with holders or bases 8 having protuberances 9 on top to receive the lower ends of the stakes 2. Each holder 8 will have a conical recess 10 therein opening through the upper end of the projection 9; and the lower extremity of the stake will have a conical tip 11 which can be fitted into the holder 8. The stake can thus be employed indoors by mounting it in the holder 8, which can be put into use for outdoors also if desired; or for outdoor playing the holder 8 can be discarded and the stake 2 thrust into the ground as shown in Fig. 3, the stake being driven in until its pointed end 11 is as far below the surface as is necessary to hold the stake upright. Near its upper end the stake may have colored ornamental bands 12.

The various parts, according to my inven-

tion, for playing the game of croquet are thus designed for both indoor and outdoor use and are exceedingly inexpensive and simple to construct and mount in operative position. The holders can very easily be manufactured and can be readily attached or detached according to the nature of the occasion.

It will be apparent that while I have shown and described my invention in the preferred forms, many changes and modifications may be made in the structure disclosed without departing from the spirit of the invention, defined in the following claims:

What I claim is:

1. Apparatus for playing croquet comprising a wicket and semi-circular holders with bores opening through the tops to receive the lower ends of the wicket and support the latter, the straight sides of said holders being presented toward each other to avoid obstructing the space between the lower ends of the wicket.
2. Apparatus for playing croquet comprising a wicket and holders having protuberances on their tops, said protuberances having bores opening through their upper ends to receive the lower ends of the wicket, said holders being semi-circular with the bores adjacent the straight sides thereof, the straight sides being presented toward each other when the wicket is set up to avoid obstructing the passage through the wicket.
3. Apparatus for playing croquet comprising a wicket adapted to be forced into the ground, and detachable holders for supporting the wicket without penetration of the supporting surface, said holders each being a sector of a circle and having bores closely adjacent the straight sides thereof for receiving the lower ends of the wicket, the straight sides being arranged toward each other when the wicket is set up.
4. Apparatus for playing croquet comprising a wicket adapted to be forced into the ground, and detachable holders for supporting the wicket without penetration of the supporting surface, said holders being semi-circular and having bores closely adjacent the straight sides thereof for receiving the lower ends of the wicket, the straight sides being arranged toward each other when the wicket is set up.
5. Apparatus for playing croquet comprising one or more stakes and wickets the ends of which are adapted to be forced into the ground, and detachable holders for supporting the stakes and wickets without penetration of the supporting surface, the stake holders each consisting of a circular base provided with a tapered recess for receiving the lower end of a stake, and the wicket holders each consisting of a pair of semi-circular bases provided with bores closely

adjacent the straight sides thereof for receiving the lower ends of a wicket, the straight sides being arranged toward each other when the wicket is set up.

Signed at New York in the county of New York and State of New York this 17th day of Dec., A. D. 1928.
